PORTABLE SANDBLAST MACHINE

John C. Darab, Wilkes-Barre, Pa.

Application June 16, 1951, Serial No. 15,574

Term of patent 7 years

(Cl. D62—2)

To all whom it may concern:

Be it known that I, John C. Darab, a citizen of the United States, residing at Wilkes-Barre, Luzerne County, Pennsylvania, have invented a new, original, and ornamental Design for Portable Sandblast Machine, of which the following is a specification, reference being had to the accompanying drawings, forming a part hereof wherein Figure 1 is a perspective view of a portable sandblast machine embodying my new design, and Figure 2 is a perspective view, on a somewhat reduced scale, taken from a point diametrically opposite from the view of Figure 1.

I claim:

The ornamental design for a portable sandblast machine, as shown.

JOHN C. DARAB.
